UNITED STATES PATENT OFFICE

JAMES E. BUSHNELL, OF NORTH PLAINFIELD, NEW JERSEY, ASSIGNOR TO RANSOME CONCRETE MACHINERY COMPANY, OF PLAINFIELD, NEW JERSEY, A CORPORATION OF NEW JERSEY

LIQUID TANK FOR CONCRETE-MIXING APPARATUS

Application filed May 2, 1928. Serial No. 274,415.

The present improvements relate, in general, to concrete mixing apparatus and more particularly to a water measuring means used in conjunction therewith.

In devices adapted for preparing freshly mixed concrete for placement, it has become of increasing importance that a definite proportion of water and dry aggregates, etc., be maintained for each given batch. As the proportions for each batch to be mixed, may vary, it is essential that a measuring means for the water be provided which, not only will accurately measure the quantity to be discharged into the mixer but also will be rugged and durable, simple to operate, have a minimum of parts and function with equal accuracy on all grades in which the apparatus may be positioned.

The present improvements accordingly, have as their primary object among others, the provision of a measuring tank, embodying the foregoing desirable features, and having means positioned within the tank for predetermining the discharge therefrom.

Another important object is to provide means for reducing the effective water surface within the tank, so that when operating on grades or under other unfavorable circumstances, the quantity of water affected by the consequent tilting of the tank due to the water seeking its own level, is reduced to a minimum.

Various other objects and advantages of the present improvements will be apparent to those skilled in the art upon reference to the accompanying drawing in which

The figure illustrates a water tank in section, embodying the present improvements.

The measuring tank 1 is mounted on or adjacent the concrete mixing machine and is conveniently positioned with respect to the charging opening of the rotary drum of said machine whereby the measured contents of the tank may be discharged through pipe 7 into said drum. The general organization of such a mixer is well known and comprises, among other elements, means for introducing cement, aggregates, water, etc. into a rotary mixing drum to be commixed preparatory to placement.

Means for admitting water to the tank 1 comprise supply conduit 2, T 3, pipe 4 and elbow 5, all being controlled by valve 6 in conduit 2. Although an independent discharge line for the tank may be provided, for convenience of assembly and simplicity, the discharge from the tank is effected through elbow 5, pipe 4, T 3 and discharge pipe 7. The latter pipe controlled by valve 8, leads to and discharges into the mixing drum, along with the cement, dry aggregates, etc., from a skip (not shown). Obviously when charging tank 1, valve 6 is open and valve 8 is closed, while upon discharge of the tank, valve 6 is closed and valve 8 open. Preferably, but not necessarily, these valves are interconnected for simultaneous actuation, and may be either operated manually, or by a connection running from the pivoted skip whereby they are responsive to elevating and lowering of said skip, all so arranged that the tank and skip may be charged and discharged simultaneously.

Mechanism of the character described and claimed in the U. S. Patent No. 1,691,031, granted Nov. 13, 1928 to Helge A. Burle, may be provided for insuring proper sequential operation of the valves 6 and 8.

The tank 1 is provided with a clean-out port or drain 9, water gauge 10 and vent valve 11. If desired, the vent valve 11 may be replaced by an overflow pipe, the water from supply conduit 2 being turned off when the tank is full, as indicated by discharge through such overflow pipe.

A vertically movable vessel, casing or drum 12 is disposed within the tank 1, being of slightly less diameter than said tank, so that a small clearance 25 exists between the respective vertical walls thereof. Said drum is conveniently suspended for vertical movement on screw shaft 13, one end of which enters said drum through threaded nut 14. Said shaft 13 projects through the tank and has keyed thereto or otherwise connected therewith, at its outer end, a hand wheel 15 having a gear 16 rotatable therewith. By rotating said wheel, the drum 12 is caused to travel vertically within tank 1, through

the coaction of screw shaft 13 and nut 14. Rotation of the drum is prevented by reason of contact between elbow 5 and the walls of a vertical recess 17 in drum 12.

5 Indicating means 18, actuated by gear 16 through gear 19, are provided for indicating the quantity of water discharged from the tank. A small receptacle 20 having perforations 21 and weep-hole 22, is fixed above and 10 in alignment with elbow 5. Said receptacle is substantially of the same size as recess 17 in drum 12 and is positioned so as not to interfere with the vertical travel of said drum. One or more ports 23 are provided in the 15 top of drum 12, and a valve controlled drain 24 is located in the base thereof.

As illustrated, the drum 12 occupies a substantial portion of the interior of the tank and when positioned at the lower extremity 20 of its travel, it occupies substantially the entire area of the tank 1 beneath inlet and outlet elbow 5. The diameter of drum 12 is slightly less than that of tank 1, so that the former has freedom of movement within the 25 tank. The clearance indicated at 25 between the tank and drum walls is thus reduced to a minimum.

The tank 1 may be filled in any position of drum 12. Upon opening of supply valve 6, 30 water enters the tank through elbow 5 descending through recess 17. When the water level reaches the base of drum 12, it ascends around the drum, through clearance 25 and recess 17 until the level reaches the top of the 35 drum. Water then enters drum 12, by way of ports 23, until filled, whence the level rises filling receptacle 20, in time the entire tank and ultimately closing vent valve 11. It will be noted that the water pressure 40 obtaining on the exterior of the walls of the drum is equalized by the water present within said drum, so that no undue strain is placed on the drum walls. This provision is particularly important and desirable 45 where large units are required thereby necessitating the use of large tanks. In such installations the inner drum is called upon to withstand enormous water pressure and is of such a size as to require the equalizing 50 means to prevent collapse.

Assuming that the tank has been filled with the drum in the illustrated position, to discharge the tank, valve 6 is closed and valve 8 opened whereby all the water in the tank 55 above the level of the mouth of elbow 5 except that in drum 12 and receptacle 20, is discharged by gravity through pipe 7 to the mixer. After the initial filling of the tank, subsequent filling thereof may be accomplished 60 more speedily since the drum 12 and receptacle 20 remain full, the dripping from weep-hole 22 in the latter being negligible.

Should it be desirable to discharge a smaller quantity of water than that dispensed in 65 the operation above described, the hand

wheel 15 is rotated until indicator 18 designates the desired quantity, at which time the drum 12 is simultaneously elevated to dotted line position, for example. The water space between the top (full line) of drum 12 and the top (dotted line) of same, being occupied by the drum, is of course eliminated 70 from the effective discharge of the tank and said space is transferred, so to speak, to the lower portion of the tank, beneath outlet 5, 75 where the water occupying same cannot escape to the mixer.

Accordingly, the water discharged from the tank with the drum in dotted line position, comprises that amount above the drum, 80 and obtaining in the annular clearance space 25, and also that between the walls of receptacle 20 and recess 17, which is above the level of elbow 5. It is thus seen that the effective discharge of the tank may be varied 85 without affecting its capacity. Furthermore, the drum may be set at any desired position in the tank, thus displacing a portion of and reducing the effective discharge area 90 thereof.

When the drum is in dotted line position, receptacle 20 displaces the water which would otherwise obtain in recess 17, so that a minimum water space is maintained 95 below the level of the drum top.

It is not uncommon for mixing apparatus of the type carrying measuring tanks, to be set up for operation on uneven terrain or on 100 grades, with consequent false measuring of the water due to variations caused by the water within the tank seeking its own level. Depending upon the direction of the tilting of the tank, the water discharged may be greater or less than that indicated as required. As requirements for a concrete mixture 105 with respect to the prescribed proportions of the ingredients, are rigidly enforced by inspection, it is essential that any deviation above or below the determined quantity of water, be reduced to a minimum and held within limits bracketing the fixed standard, 110 any deficiency or excess within said limits being ineffectual to mar the efficiency of the batch.

When a mixer, having a tank embodying 115 the present improvements, is positioned on a grade or under similar conditions, the water obviously will seek its own level. Let it be assumed that the drum 12 is set anywhere in the tank, e. g., at the dotted line position, and has been filled with water as described. Upon discharge, as the water level recedes, said level will be in a plane at an angle to the normal horizontal of the tank, due to the inclination of the tank, causing a higher water 120 level on one side of the tank than at the opposite side.

In that portion of the tank above the drum-top, this difference in level represents an appreciable area embracing a substantial vol- 125

ume of water on one side of the axis 13, with a corresponding area on the other side of axis 13 and opposite thereto, devoid of water. Obviously, under such circumstances the volume discharged through an outlet positioned in this portion of the tank would be materially affected, a substantially greater or less amount than the measured quantity desired, being discharged, depending of course, upon 10 the direction of inclination of the tank with respect to the outlet.

However, with the present improvements this water surface or area is reduced to a minimum at the discharge outlet by the presence of the drum 12. As is apparent, the drum occupies substantially the entire cross-sectional area affected by the inclination of the water level, and previously referred to, save only a small annular space represented by 25. The area of this annular space 25 is obviously very small in comparison with the entire cross sectional area of the tank. Accordingly, when the level recedes below the top (dotted line) of the drum, the water 25 seeks its own level in the small annular space 25 and the volume of water therein, which is affected by the inclination of the tank, is but a small fractional part of the volume previously noted, so that the measured volume to be discharged is affected only by an inappreciable increment above or below the fixed standard, as the case may be. It is understood that the above description is applicable to any position of the drum.

It is thus seen that the effective water level of the measured volume is reduced to a minimum, so that, with the present improvements, the measured discharge from the tank is unaffected, in any material proportion, by unfavorable working conditions, such as grades, etc. Applicant has accordingly devised a measuring tank operable with equal accuracy under favorable or unfavorable conditions and one which may be universally applied to all apparatus adapted for the measuring of liquids.

Various modifications within the scope of the present improvements, will be apparent to those skilled in the art and may be adopted 50 without departing from the scope of the invention.

I claim.

1. In a device of the character described, the combination of a water tank having a 55 port, a drum within said tank movable relative to said port for varying the discharge from the tank without affecting the capacity thereof, said drum provided with pressure equalizing means and mechanism for varying 60 the position of said drum.

2. In a device of the character described, the combination of water tank having a port, a drum having a perforate top suspended in said tank having its vertical walls spaced 65 from said tank for effecting a minimum clear-

ance therebetween and means for moving said drum.

3. A tilttable water measuring tank comprising an outer casing having a port, in the side thereof, an inner casing slidable in said tank and having limited clearance therewith, means for moving and setting said inner casing, all so constructed and arranged that when the tank is discharged in inclined position the cross sectional area of the water affected by such incline is reduced to a minimum. 70 75

4. A liquid measuring device for concrete mixers comprising a tank mounted on a movable base, a vessel within said tank, one portion of said vessel having a cross sectional area slightly less than that of said tank whereby an annular area is provided between said members and discharge means for said tank communicating with said annular area. 80 85

5. A liquid measuring device for concrete mixers comprising a tank, a drum within said tank, a portion of said drum having a cross sectional area slightly less than that of said tank whereby an annular area is provided 90 between said members, and discharge means for said tank positioned in the side thereof and communicating with said annular area.

Witness my hand, this 25th day of April, 1928, county of Middlesex, State of New Jersey. 95
